CLAIM

The ornamental design for a chair with end panel, as shown.

DESCRIPTION

FIG. 1 is a perspective view of a chair with end panel showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a perspective view thereof on a reduced scale in association with a series of chairs which are shown in broken lines for illustrative purposes only and form no part of the claimed design.
